UNITED STATES PATENT OFFICE.

CHARLES A. BERRY, OF STAMFORD, CONNECTICUT, ASSIGNOR TO THE YALE & TOWNE MANUFACTURING COMPANY, OF STAMFORD, CONNECTICUT.

LOCK.

959,293.

Specification of Letters Patent.

Patented May 24, 1910.

Application filed June 10, 1909. Serial No. 501,418.

To all whom it may concern:

Be it known that I, CHARLES A. BERRY, of Stamford, in the county of Fairfield and State of Connecticut, have invented certain new and useful Improvements in Locks; and I do hereby declare the following to be a full, clear, and exact description of the invention, such as will enable others skilled in the art to which it appertains to make and use the same.

My invention relates to improvements in locks designed particularly for use on doors between rooms.

For hotel and similar uses it is desirable to have a lock so arranged that adjoining rooms may be used en suite or as separate rooms, and the object of the invention is to provide a lock which may be used as an ordinary knob latch, with means operable from each side of the door whereby it may be locked from either side.

A further object is to provide means whereby the locking means can be dead locked either in their operative or inoperative position.

With these and other ends in view my invention consists in the parts and combinations of parts as will be more fully explained and pointed out in the claims.

In the accompanying drawings, Figure 1 is a view in elevation of my improved lock, the cover plate being removed. Fig. 2 is a view in section on line $\alpha-\alpha$ of Fig. 1. Fig. 3 is a view in section on the line $y-y$ of Fig. 1; and Fig. 4 is a view on the line $z-z$ of Fig. 1.

In the drawings, I have shown the lock composed of an inside plate 1 an outside plate 2 and an inner case 3 containing the lock mechanism.

The knobs 4 are mounted in the plates 1 and 2, and each knob is connected to and actuates a hub or roll back 5, which latter in turn engages the turned ends 6 of the tail piece 7. This tail piece is connected by the link 8 with the latch bolt 9, and is operated by the hubs or roll backs to retract the latch bolt 9, the latter being yieldingly held in its projected position by the spring 10.

I would have it understood however that my improvements to be hereinafter described are applicable to other types of locks hence I do not confine the use of the invention to the type of lock shown, and above 55 described.

Mounted in the lock case 3 above and below the latch bolt 9, are the bolts 11, each of which is actuated by a cam hub 12 mounted in the lock case, one on each side of the door, as shown in Fig. 3. Each cam hub is rotated by a thumb piece 13, one of which is mounted in the outer plate 1 and the other in the inner plate 2, and each thumb piece is provided with an angular shank 14, which fits within the angular opening 16 in its respective cam hub 12. The cam 12^a of each cam hub 12, rests within a recess 17 in its bolt, the end walls of the recess, at 18 being cut away as shown, so as to form seats for the ends of the cams 12^a, both when the bolts are projected and also when they are retracted, thus deadlocking the bolts in their two positions.

Each cam hub 12 is yieldingly held, in its two positions, as shown in Fig. 1, by a spring 19 secured to the post 20 on its bolt 11, and bearing at its free end against the shoulder 21 formed integral with the hub 12. These springs prevent any accidental 80 rotation of the hubs, and operate to hold the cams against their seats 18, thus deadlocking the bolt in its two positions.

Each bolt 11 is provided with an inwardly projecting lug 22, located behind and in the plane of the turned end or stop 23 of plate 24 secured to the latch tail piece 7. When either bolt 11 is projected, its lug 22 rests close up to, and in the path of the stop 23 carried by the tail piece, and prevents the latch bolt from being retracted by either knob.

Loosely mounted on the rear end of lock case 3 is the sliding plate 24^a provided with the forwardly projecting arms 25 terminating in bent ends 26 which form deadlocking abutments. These deadlocking abutments are adapted to be moved into the path of movement behind both bolts, when the latter are projected and thus deadlock the lat- 100

ter, and are also designed to be moved into the slots 27 formed in the bolts, when the latter are retracted, and thus lock the latter against manipulation by the thumb pieces.

In Fig. 1, I have shown one dead bolt locked in its projected position and one in its retracted position, the projected bolt also deadlocking the knob mechanism through the parts 22 and 23 before described. This sliding plate 24^a is operated by a key through the knob cylinder 28, connecting bar 29 and hub 30. This hub is provided with a cam 31 which is moved by the turning of the hub 30 into position between the shoulders 32 formed by slotting the sliding plate 24^a. With the parts in the position shown in Fig. 1, one bolt is locked in its projected position and the other in its retracted position, and the cam 31 is shown (in dotted lines) in a position to engage the upper shoulder 32 of plate 24. By continuing the movement of the cam, by the key as above explained, the plate 24 will be moved upwardly thus carrying its abutments 26 up into a plane above the bolts, thus freeing the latter and permitting either bolt to be actuated by its thumb piece. By now turning the cam 31 in the opposite direction, the sliding plate will be moved to its position to deadlock one or both bolts.

The sliding plate is held in its two positions by the bend in spring 33 engaging recesses 34 in one edge of sliding plate 24.

With this lock both dead bolts may be left free to be actuated by the thumb pieces; or they may be deadlocked in the retracted position thus converting the lock into an ordinary knob latch, or they or either of them may be deadlocked in their projected positions by the key thus preventing the door from being opened except by the use of the proper key.

It is evident that many slight changes might be resorted to in the relative arrangement of parts shown and described without departing from the spirit and scope of my invention hence I would have it understood that I do not wish to confine myself to the exact construction and arrangement of parts shown and described, but,

Having fully described my invention what I claim as new and desire to secure by Letters-Patent, is:—

1. In a lock, the combination with a latch bolt and knob mechanism for actuating same, of a dead bolt, a cam for moving the dead bolt to its two positions and for deadlock-
ing it in each position, means for turning the cam, and coöperating projecting mem-
bers on the dead bolt and latch mechanism,
whereby when the dead bolt is projected, the
knob mechanism of the latch will be dead-
locked.

2. In a lock, the combination with a latch 65 bolt, and knob mechanism for actuating same, of two dead bolts, independent means for moving each dead bolt to its two positions and for deadlock-
ing it in each position and coöperating projecting members on the latch 70 mechanism and both dead bolts, whereby when either bolt is projected the knob mechanism of the latch will be deadlocked.

3. In a lock, the combination with a latch 75 bolt and knob mechanism for actuating same, of two dead bolts, independent means for actuating the bolts, coöperating project-
ing members on the latch mechanism and both bolts whereby when either bolt is pro-
jected the knob mechanism of the latch will 80 be deadlock-
ed, and a single mechanism actuated by a key for deadlock-
ing both bolts.

4. In a lock, the combination with latch 85 mechanism, of a dead bolt, means for actu-
ating same, coöperating means on the latch mechanism and bolt, whereby when the bolt is projected, the latch mechanism will be deadlock-
ed, and key actuated mechanism carried by the lock casing for deadlock-
ing the bolt in its two positions.

5. In a lock, the combination with latch 95 mechanism, of two dead bolts, means for inde-
pendently actuating the bolts, coöperating
means on the latch mechanism and both
bolts whereby when either bolt is projected
the latch mechanism will be deadlock-
ed, and a single mechanism actuated by a key for
deadlock-
ing both bolts irrespective of their
positions.

6. The combination with latch mechan- 100 ism, of a dead bolt, means for actu-
ating same, coöperating projecting members on the latch mechanism and dead bolt whereby when the bolt is projected the latch mech-
anism will be deadlock-
ed, and key actuated 105 mechanism adapted to engage said dead bolt in advance of its rear end for locking same in its retracted position and also adapted to engage the bolt in rear of said first men-
tioned point of engagement for locking the 110 bolt in its projected position.

7. The combination with latch mechanism, 115 of a bolt, a cam actuated by a thumb piece for shifting said bolt, the said cam also act-
ing as a dead lock for the bolt, a spring for yieldingly holding the cam in its two posi-
tions, and a key actuated device directly en-
gaging the bolt for deadlock-
ing it in its two positions.

8. The combination with latch mechanism, 120 of two bolts, cams actuated by thumb pieces for shifting the bolts, and a key actuated deadlock-
ing device adapted to be shifted to directly engage and deadlock both bolts,
either in their projected or their retracted 125 positions.

9. In a lock, the combination with a latch bolt and knob mechanism for same, of a bolt,

a cam for moving said bolt to its two positions, coöoperating projecting members on the bolt and latch mechanism, whereby when the bolt is projected the knob mechanism will be deadlocked and key actuated mechanism for deadlocking the bolt.

In testimony whereof, I have signed this

specification in the presence of two subscribing witnesses.

CHARLES A. BERRY.
